UNITED STATES PATENT OFFICE.

EDMUND H. FARQUHAR, OF SCHENECTADY, NEW YORK, ASSIGNOR TO GENERAL ELECTRIC COMPANY, A CORPORATION OF NEW YORK.

BUCKET FOR TURBINES.

No. 901,961.

Specification of Letters Patent.

Patented Oct. 27, 1908.

Application filed April 7, 1906. Serial No. 310,416.

To all whom it may concern:

Be it known that I, EDMUND H. FARQUHAR, a citizen of the United States, residing at Schenectady, county of Schenectady, State of New York, have invented certain new and useful Improvements in Buckets for Elastic-Fluid Turbines, of which the following is a specification.

The present invention relates to vanes, blades or buckets for elastic-fluid turbines, and has for its object to improve their construction.

In carrying out my invention I employ buckets which are made of a hot rolling alloy, for example, I prefer to use buckets that are made by the so-called "extruding" process on account of their superior qualities both as to wear and finish and the facility with which they may be united to their support. By making buckets of this character, each can be formed with smooth, hard surfaces and accurately made to the desired dimensions with the necessary knife-like edges. Such a bucket will last for a long time without showing the effects of the action of steam or other elastic fluid thereon, and is non-corrosive. The buckets are smooth and hard when new and under the action of the steam will retain the smooth finish and will not pit or be otherwise injured in service. The buckets are fused into a base by pouring molten metal at a relatively low temperature around the ends thereof, the said buckets being placed in a suitable mold, and so arranged that the ends to be fused project the required distance into the space arranged to receive the molten metal. By using an alloy of suitable composition and a metal for the base or support of similar character, I find by actual practice that the buckets will be fused thereto and the sharpened edges at the entrance and exit will not be injured by the heat transmitted thereto by the molten metal at the time the base or support is formed. I have found that an alloy composed of a large portion of copper and a smaller amount of spelter mixed with a small quantity of an alloy of copper, nickel and iron is well adapted to produce the desired results. Great care has to be exercised in choosing the proper compositions and temperature of the molten metal, since otherwise the thin sharp edges will be destroyed on one hand or the buckets will not be properly united

to the base on the other. The metal of which the base is formed should be of such a character that it will flow readily and fuse with the bucket ends at a relatively low temperature. In casting the support around the bucket ends the buckets are held in position in the mold in such manner that the proper pitch and relation between buckets is preserved, as well as the entrance and exit angles correct for the machine for which the buckets are intended.

I may use my invention in connection with radial or axial flow, reaction or impulse machines or a combination thereof. In the case of an axial flow machine the buckets occupy radial positions and the pitch distance between them for a given bucket element is a constant factor. In the case of a radial flow machine the buckets occupy a position parallel to the axis of the turbine and the base or support is fused to the buckets on one end or the other as best suits the construction of the machine. The pitch distance between buckets is of course preserved and also the alinement circumferentially and laterally.

I find it desirable to fasten the outer ends of the buckets together by a suitable strip or cover, which is preferably secured in place by tenons formed integral with the ends of the buckets opposite the base or support. The covers are provided with openings corresponding in shape and size to the tenons, and the latter are afterward riveted over to secure the cover in place.

My invention is particularly applicable to those machines requiring long buckets which could not be satisfactorily cut by a bucket-cutting machine out of solid stock, but is also applicable to shorter buckets.

By reason of my invention I am able to dispense with machining on the buckets after they are put in the molding sand or in the core where the latter method of procedure is followed. Whatever finishing on the buckets is necessary is done before this particular operation.

By means of my invention I am able to greatly decrease the cost of manufacture, firmly secure the buckets to their base or root, decrease the number of small parts which have to be made and machined, and also provide spaces for the steam or other elastic fluid between the buckets which are free from rough spots or depressions which

tend to create eddies as the steam flows through the spaces, resulting in loss in efficiency.

In the accompanying drawing, which illustrates one embodiment of my invention, Figure 1 is a view in side elevation of a part of a bucket segment; Fig. 2 is a cross-section of the same; Fig. 3 is a slight modification showing a somewhat different form of support; and Fig. 4 is a detail view of a bucket before it is fused to its support.

1 represents the base of the bucket segment which may be of any suitable length or construction. Ordinarily these segments are made of such a length that they may be conveniently handled, and each is provided with a plurality of buckets 2 either radially or otherwise disposed and fused thereto. The buckets are made of a hot rolling alloy either by extruding dies or otherwise. They are all finished as to dimensions and surface before they are put in the mold, and the base cast around the ends. The buckets are provided with tenons 3 of suitable shape and size to secure the cover or shrouding ring 4 in place. These buckets may be mounted on the revolving element of the turbine or on a stationary element as desired.

30 In Fig. 2 is shown a wheel or carrier 5 adapted to support the base 1 of the buckets. Provision is made in this case for two rows of wheel buckets on each wheel, but the number can be increased or decreased by properly modifying the form of the support. In this instance the base is provided with a shoulder 6 that enters a groove in the wheel and the bases are retained by axially extending rivets 8, the rivets passing through the bases on opposite sides of the wheel so that a single set suffices for securing two rows of wheel buckets.

In Fig. 3 a base 1 of somewhat different construction is shown. This base is more particularly adapted for the stationary buckets, but its use is not limited thereto. In this case, as before, the buckets 2 are of the same construction and are fused into the base and are provided with a cover 4 secured in place by tenons 3 having the outer ends thereof riveted over. Where the buckets are long, such as six or eight inches for example, the cover 4 not only serves to form one wall of the fluid space, but also serves to fasten the buckets together at their free ends and form an additional means of support. The cover and the base are preferably made somewhat wider in all cases than the buckets so that any accidental rubbing will take place thereon instead of on the sharpened edges of the buckets. By means of the construction shown I am able to provide a bucket which can be operated with greater clearances than where no cover is provided, and by arranging the cover as

described I am able to dispense with the wires or strips which have heretofore been employed to tie the outer ends of long buckets together, these wires or strips being located at some little distance from the free ends of the buckets. These wires or strips are objectionable for the reason that they interfere with the free passage of steam through the bucket spaces and in this manner create eddies resulting in a decrease in efficiency of the turbine.

In Fig. 4 is shown a bucket before it is fused to its support. Each bucket is provided with a tenon 3 formed integral therewith, but I may omit the tenons on some of the buckets if desired where the latter are short and the strains are not excessive. The root of the bucket is preferably but not necessarily provided with one or more recesses of suitable shape and size to receive the molten metal at the time the base is cast and form an additional and mechanical securing means. The recess may be on one or both sides of the bucket or extend completely through it as desired.

Tests have shown that buckets made in accordance with my invention will stand a strain of 31,000 pounds without affecting the union between the root of the bucket and the base.

A test run of 1064 hours was made with buckets made in accordance with my invention, which showed less wear than on those cut from solid steel. In addition to the increased life, there is a great decrease in the cost of manufacture over other constructions.

The following gives a good idea of the properties of the buckets now in commercial production: elastic limit, 25,000 pounds; tensile strength, 70,000 pounds; elongation in 2", 36 per cent. reduction of area 50 per cent. The wheel buckets commonly have a peripheral speed of from 350 to 450 feet per second, and the strains thereon due to centrifugal force are of necessity high, hence the importance of making a secure union with the support.

Separately formed buckets have heretofore been secured in place by a calking strip or strips or by a ring having slots cut in one side, the metal between buckets being forced into engagement with the concave and convex walls thereof. Such arrangements are objectionable for many reasons, of which the following are the principal: The buckets are held merely by the friction between them and the holding strip or ring, resulting in an insecure support. The centrifugal strains on these buckets are very great and when one of them lets go it usually results in wrecking the turbine, or at least injuring it to such an extent that it takes a long time to repair it. Instances are known of it having taken weeks to repair a machine after such an accident and put it in working condition. Again, the

cost of the said construction is high and it is a difficult matter to fasten the buckets, or blades as they are sometimes called in place. This difficulty is greatly enhanced where a 5 large number of rows are mounted on a common support such as a revolving drum or on the inside of a wheel casing. The character of the retaining ring at the base or root of the buckets is such that small crevices are 10 inevitable, and these result in the creation of objectionable eddies. It is always a difficult matter to properly align the buckets, and where they are long and the above mentioned arrangements used the difficulty is greatly increased.

15 In accordance with the provisions of the patent statutes, I have described the principle of operation of my invention, together with the apparatus which I now consider to 20 represent the best embodiment thereof; but I desire to have it understood that the apparatus shown is only illustrative and that the invention can be carried out by other means.

25 What I claim as new and desire to secure by Letters Patent of the United States, is,—

30 1. In an elastic-fluid turbine, the combination of a plurality of buckets made of a hot rolling alloy, a cast-metal support to which the buckets are fused, and a carrier for the support.

35 2. In an elastic-fluid turbine, the combination of a plurality of buckets each having a concave and a convex wall and made of a hot rolling alloy, a cast-metal base to which the buckets are fused at one end, a means for

connecting the opposite ends of the buckets to hold them in alignment and preserve the pitch distance, and a carrier for the base.

3. In an elastic-fluid turbine, the combination of a plurality of buckets each being 40 separately formed and provided with concave and convex walls, a base to which the buckets are secured by fusing, tenons on the buckets, a cover or shroud that is secured to the buckets by the tenons, which forms one 45 wall of the fluid passage, preserves the pitch relation between the buckets and assists in securing the buckets against centrifugal strains, and a carrier for the base.

4. In an elastic-fluid turbine, the combination of a plurality of buckets each being 50 made of extruded metal and provided with a recess at one end, tenons formed integral with the buckets, a cast-metal base to which the buckets are fused, the metal of the base 55 filling the recesses and forming an additional mechanical support, a cover for the buckets which is secured thereto by riveting over the ends of the tenons, the said cover acting as a mechanical support to resist centrifugal strains and also to preserve the pitch distance between buckets and hold them in alignment against lateral displacement, and a carrier for the base.

55 In witness whereof, I have hereunto set 60 my hand this fifth day of April, 1906.

EDMUND H. FARQUHAR.
